PICKER CHECK STRAP

Victor Gravitt, Chickamauga, Ga., assignor to
Page Belting Company, Concord, N. H., a corporation of New Hampshire

Application November 21, 1950, Serial No. 196,759

10 Claims. (Cl. 139—165)

1

This invention relates to looms of the type having a reciprocating shuttle operated by a picker stick, and, more particularly, to a check strap for the picker stick.

In the ordinary loom construction the movement of the picker stick is checked in each direction by a strap, the ends of which are brought together and secured by a suitable clamp attached to the loom frame, other portions of the strap being held in position by suitable guides. The strap is thus given the general form of a relatively flat ellipse surrounding the picker stick. The picker stick, which is pivoted on the loom frame at some distance below the shuttle guide, swings back and forth within the elliptically formed check strap.

The main object of the present invention is to provide a loom incorporating a novel check strap and strap guide rod which is fixed to the shuttle guide of the loom, said guide rod having its respective ends bent inwardly at an angle to act as stops for the check strap. The check strap embodies a strip of leather having openings in its respective ends whereby the same is mounted on the rod for free reciprocatory motion and, further and more important, the check strap has some rotary or angular motion with respect to the rod whereby, when the end portion of the check strap is engaged by the picker stick, the check strap will rotate slightly on the rod, the inner surface of the strap thereby taking the same inclination as the side surface of the picker stick whereby wear on the check strap is greatly reduced.

A further object of the invention provides a fixed rod mounted on the shuttle guide, the rod being bent to form a loop at its center portion, whereby the same can be attached as by a clamp to the bracket which is fixed to the shuttle guide, the respective ends of the rod being bent at a ninety degree angle to form a stop for the respective ends of the check strap.

A further object of the invention incorporates a check strap made up of two leather straps or belting, one being longer than the other, the shorter one fitting within the longer one, and during the movement of the checker strap to its respective extreme positions a certain friction is created between the respective straps to cause a braking action.

A still further object of the invention is to provide the longer check strap at its outer end and on its outer surface with a reinforcing piece of leather which is adapted to contact the bent ends of the rod when the check strap is moved to either

2

of its extreme positions and thereby act as wear strips for the check strap.

Other objects and advantages will become apparent when taken in connection with the accompanying drawings, in which—

Fig. 1 is a view in side elevation illustrating certain parts of the picker mechanism of a loom, having a check strap of a single thickness embodying this invention applied thereto;

Fig. 2 is a view in side elevation illustrating certain parts of the picker mechanism of a loom, having a check strap of double thickness, that is a check strap formed of two different length strap members, embodying this invention applied thereto;

Fig. 3 is a sectional view of the picker mechanism taken substantially on the line 3—3 of Fig. 2 and showing the check strap in its extreme right-hand position;

Fig. 4 is a view similar to Fig. 3 showing the check strap moved to its extreme left-hand position;

Fig. 5 is a top plan view of the inner strap member of the check strap;

Fig. 6 is a top plan view of the outer check strap member;

Fig. 7 is a side view of the strap shown in Fig. 6 showing the reinforcing members mounted at the respective ends of the outer check strap; and

Figs. 8 and 9 show a modified form of a check strap guide rod in which the respective inner portions thereof are welded together to form a central loop rather than being looped as in the construction shown in the other figures.

Referring specifically to the drawings, in which like numerals have been applied to indicate similar parts throughout the various views, the invention is shown as applied to the picker mechanism of a loom comprising a fixed shuttle guide indicated at 6, including a shuttle 7 which is adapted to be mounted for reciprocating movement on the shuttle guide, and a picker stick 8 which is pivoted to the loom frame at a point not shown for reciprocating movement, said picker stick including a contact block 9 mounted thereon for engagement with the shuttle 7.

A bracket 10 is fixed as by screws 11 to the shuttle guide 6, the bracket 10 terminating in an end 12 which is provided with an opening to receive a bolt 13 and a nut 14. A check strap guide rod 15 is bent to form at its middle portion a loop 16 through which the bolt 13 is adapted to pass, whereby the guide rod for the check strap is adapted to be rigidly mounted to the bracket

10 and thereby fixed to the shuttle guide 6 of the loom.

In Fig. 1 the guide rod 15 is shown as fixedly mounted to the bracket 10, the guide rod 15 having mounted thereon a single thickness leather check strap 17 and, as will be seen, the check strap has been moved, as by the picker stick 8, to its extreme right-hand position, the strap 17 having been moved along the rod 15 and the strap having been slightly angularly rotated whereby the inner surface thereof has taken the same inclination as the surface of the picker stick.

However, the preferred embodiment of the invention includes a double thickness of check strap as illustrated in Fig. 2, the inner ply of which is shown at 18 and the outer ply of which is shown at 19. Each of the check strap elements has punched therein at its respective ends a hole member 20, which, of course, is adapted to mount the guide rod 15. The outer check strap is provided with a reinforcing member 21 which engages with the inturned ends 22 of the guide rod 15.

Likewise as illustrated in Fig. 2, the check strap at its end portion has angularly moved with respect to the guide rod 15 so as to take an inclination exactly the same as that of the side of the picker stick 8 whereby wear on the strap is greatly reduced. Also, the reinforcing strip 21 acts as a wear strip when the strap is moved against the rod stop 22. In the reciprocation of the check strap, as seen in Fig. 2, the respective plies 18 and 19 of the strap are caused to move, one with respect to the other in friction contact with each other, the friction between the two straps increasing as the check strap approaches either of its extreme right or left hand positions, said friction between the two straps thereby setting up a considerable amount of braking action which has the result of braking the check strap movement when the same is reaching either of its extreme positions. Also the reinforcing strips 21 bear against the guide rod to provide braking action. This is particularly so as to the particular reinforcing strip 21 which is remote from the end of the check strap which is being actuated by the picker stick (see Fig. 3). In other words, the pull on the strap 18 rocks the strip 21 at the trailing end of the strap into firm bearing engagement with rod 15.

In the modified form of the guide rod for the check strap, as indicated in Figs. 8 and 9, the same comprises two like half members 23 and 24, each half member having its inner end turned inwardly as indicated at 25 and the said respective ends being welded as indicated at 26 to each half member to thereby form a loop 27 for the accommodation of the bolt 13 for supporting the guide rod in position upon the loom. The respective outer ends of the guide rods 23 and 24 are turned at an angle of ninety degrees to form stop members 28 and 29 for the check strap, not shown.

In the modified construction illustrated in Figs. 8 and 9 and referring specifically to Fig. 8, it will be seen that the respective end members 27 and 28 are off-set with respect to each other, said offset ends providing for easier rotation or angular movement of the check strap during the reciprocation thereof.

As best seen in Figs. 1 and 2, it will be readily recognized that when the picker stick 8 engages the check strap 17 or 18, that immediately upon engagement of the picker stick with the check strap, the check strap rotates or is angularly inclined to some extent upon the guide rod 15

whereby the same takes the same inclination as that of the picker stick. Therefore, because of this feature of rotation or angular movement of the check strap there is a great deal less wear at the end portion of the check strap which normally receives the greatest wear. And, of course, in addition, the braking action created by the friction between the inner and outer straps tends to retard the movement thereof in consequence of which there is much less breakage of the check strap where the greatest wear occurs.

It will, therefore, be seen that the invention provides for a much smoother operation of the check strap and its braking effect, provides for longer life of the check strap and much less adjustment is necessary. Further, in the event of a broken check strap or a worn check strap the parts can be very easily replaced simply by removing the nut 14 from the bolt 13 whereby the guide rod 15 can be dismantled from the loom and the check strap can be slipped over the respective rod ends 22 whereby the check straps can be readily removed and readily replaced on the guide rod if and when desired and necessary.

While the preferred construction of the invention is illustrated, it is not intended that the same should be limited thereto but is capable of modification within the scope of the following claims. It will be apparent from an inspection of Figs. 1-4, inclusive, of the drawings that the stops 22 are not necessary. For instance, when the strap is actuated to the right as shown in Figs. 1-3, inclusive, the left hand end of the strap engages the mounting loop portion 16 (or 25, Figs. 7 and 8) of the rod so as to limit travel of the opposite, or picker stick-actuated end of the strap, short of the end of the rod. Such picker stick-actuated end of the strap binds on the rod as shown, so as not to be actuated off of same regardless of the presence or absence of the stops such as 22 in Figs. 1, 2 and 3.

I claim:

1. A check strap for looms comprising in combination a guide rod for the check strap, said guide rod having fastener-receiving means adjacent its center for attachment to the loom, the check strap being slidably connected to said rod at opposite sides of said fastener-receiving means, and said rod having its ends bent to form stops for the check strap.

2. A check strap guide rod for looms, comprising a rod looped at its center for attachment to the loom, the ends of the rod being bent to form check strap stops, and a check strap having a hole at each end and being slidably mounted on the guide rod.

3. A check strap for looms, comprising plies of flexible leather material consisting of a longer outer ply having secured to its outer end surfaces reinforcing tabs, a shorter inner ply having its outer surface in friction contact with the inner surface of the outer ply, each ply having openings in their ends, a guide rod mounted on the loom, said rod having its opposite ends turned at an angle to act as a stop for the check strap, said check strap mounted on the guide rod for free longitudinal and angular movement with respect thereto, said check strap forming a loop confining a picker stick of the loom, said strap moving angularly when contacted by the picker stick to present a flush surface with the picker stick, said strap reciprocating on the guide rod under action of the picker stick, and the friction between the inner and outer plies of the strap producing a

braking action as the picker stick reaches its limit of outward movement.

4. In a picker stick check strap means for looms, a check strap having free ends, a guide rod extending longitudinally of said strap and having fastener-receiving means intermediate its ends whereby said rod is mountable on a loom, said check strap having means adjacent opposite ends slidably connecting the strap to the rod at opposite sides of said fastener-receiving means, and the latter, in the operation of the loom, engaging whichever end of the strap that is remote from the picker stick to limit movement of the strap longitudinally of the rod.

5. The combination set forth in claim 1, and said check strap comprising separate plies having transverse holes adjacent their ends for the passage of said rod.

6. In a picker stick check strap means for looms, a check strap having free ends, a guide rod extending longitudinally of said strap and having fastener-receiving means intermediate its ends whereby said rod is mountable on a loom, said check strap having means adjacent opposite ends slidably connecting the strap to the rod at opposite sides of said fastener-receiving means, and laterally projecting stop means adjacent the ends of the rod, said stop means engaging and limiting endwise movement of the proximate strap end under the action of the picker stick.

7. In a picker stick check strap means for looms, a check strap having free ends, a guide rod extending longitudinally of said strap and having fastener-receiving means intermediate its ends whereby said rod is mountable on a loom, said check strap having means adjacent opposite ends connecting the latter to said rod for both reciprocating sliding movement and angular turning movement thereon, and laterally projecting stop means adjacent the ends of the rod, said stop means engaging and limiting endwise movement of the proximate strap end under the action of the picker stick.

8. In a picker stick check strap means for looms, the combination of a check strap comprising separate inner and outer flexible strap members in substantially contiguous overlying relationship and having free ends, said strap members having alignable holes adjacent said ends, the holes at the opposite ends of said inner strap member being closer together than those of the outer strap member, a guide rod extending longitudinally of said check strap and having its ends projected through the adjacent strap member holes whereby each check strap end is both slidably and rockably mounted on said guide rod, said guide rod having fastener-receiving means intermediate its ends for attachment to a loom, and laterally projecting stop means adjacent the ends of the rod, said stop means engaging and limiting endwise movement of the proximate check strap end under the action of the picker stick.

9. The combination set forth in claim 8, and a combined braking and buffer strip secured to the outer surface of the outer strap member and adjacent the outer edge of the guide rod-receiving hole therein.

10. The combination set forth in claim 6, and a combined braking and buffer strip secured to the outer surface of said check strap adjacent each end, the means slidably connecting the strap ends to the rod comprising holes through the strap ends, and said combined braking and reinforcing strip secured to each strap end adjacent the outer edge of the adjacent hole.

VICTOR GRAVITT.
